UNITED STATES PATENT OFFICE.

FRED J. ELERICK, OF BRIDGEPORT, OHIO, ASSIGNOR OF ONE-HALF TO FREDRICK
W. E. T. HAMMER, OF BRIDGEPORT, OHIO.

AUTOMOBILE-CURTAIN.

1,325,282.

Specification of Letters Patent.

Patented Dec. 16, 1919.

Application filed November 9, 1918. Serial No. 261,845.

To all whom it may concern:

Be it known that I, FRED J. ELERICK, a citizen of the United States, residing at Bridgeport, in the county of Belmont and State of Ohio, have invented certain new and useful Improvements in Automobile-Curtains; and I do hereby declare the following to be a full, clear, and exact description of the invention, such as will enable others skilled in the art to which it appertains to make and use the same.

My invention relates to improvements in means for supporting storm curtains on vehicle bodies.

An important object of this invention is to provide a curtain support adapted for attachment to the doors of a vehicle body in a highly convenient and expeditious manner, and which may be quickly removed.

A further object of the invention is to provide a storm curtain support, which is hinged at a point spaced from its upper end to permit the curtain to be arranged on the inner side of the side walls of the vehicle top and to permit of the ready opening of the doors.

A further object of the invention is to provide means for supporting the storm curtain above a body door of a vehicle in such a manner that the curtain is prevented from rattling and is retained in a rigid position with respect to the adjacent curtains, thereby preventing access of the rain and wind into the tonneau of the machine.

A further object of the invention is to provide a curtain support of the character described, which is simple to adjust, of highly simplified construction and desirable in use.

Other objects and advantages of the invention will be apparent during the course of the following description.

In the accompanying drawings forming a part of this specification, and in which like numerals are employed to designate like parts throughout the same,

Figure 1 is a fragmentary perspective of a vehicle body and top showing my improved curtain supporting means attached to one of the doors thereof.

Fig. 2 is a fragmentary side elevation of a vehicle body door having my improved storm curtain support attached thereto, the view being taken from the tonneau of the vehicle,

Fig. 3 is a side elevation of my improved curtain support,

Fig. 4 is a section through the fragment of the vehicle body, showing my improved curtain supporting means applied to the vehicle door.

Fig. 5 is an enlarged fragmentary side elevation of the support shown in Fig. 3, and

Fig. 6 is an enlarged fragmentary front elevation of the support shown in Fig. 3, parts thereof being shown in section.

In the drawings, wherein for the purpose of illustration is shown a preferred embodiment of my invention, the numeral 10 designates a vehicle body, having a top 11, which in this case is of the one man type. The top 11 includes longitudinally extending sides 12 having supporting bows 13 along their upper portions. Doors 14 hingedly secured as at 15 to the body 10 are provided.

The usual storm curtains 16 extend from the upper edge of the body 10 to the side wall 12 of the top. Arranged above the doors 14 and attached thereto are curtains 17. Each curtain 17 is attached to the upper portion of the door 14 by buttons 18 engaging suitable button holes in the lower portion of the curtain. As clearly shown in Fig. 2, the curtain 17 has its upper portion 19 arranged behind one longitudinal side wall 12 of the top 11, thereby preventing access of the wind and rain to the tonneau of the machine.

The vertical edge portion of the curtain 17 which is arranged in a vertical plane of the hinges 15, may be secured to the adjacent curtain 16 by suitable fastening devices 20. As clearly shown in Fig. 4, I have provided a door storm curtain support 21. The curtain support 21 is of a suitably stout metal and has its lower end portion extending into a socket 22 carried by the inner side of the door 14 along its upper portion at a point adjacent its free vertical edge. The socket 22 is secured to the door 14 by suitable screws 23. The curtain support 21 is provided with an offset portion 24 at a point spaced from its lower end. The offset portion 24 rests upon the top of the door 14 and brings the body portion of the support flush with the outer side of the door, thereby retaining the curtain perfectly smooth. As shown in Figs. 1 and 2 the arm 21 is provided intermediate its ends with a horizontal 110

extending arm 25 having a fastening device 26 for engaging the outer vertical edge of the curtain 17, for supporting the same rigidly with relation to the adjacent curtain 16.

As clearly shown in Figs. 2 and 4, an arm 27 is hingedly connected to the upper portion of the support 21. The lower end of the arm 27 and the upper end of the support 21 are provided with a pair of coacting locking plates 28 having centrally disposed openings 29 for receiving a hinge pin 30. A lug 31 is provided on one of the coacting locking plates 28 and is adapted to extend into recesses 32 in the other plate. A coil spring 33 arranged on the hinge pin 30 is adapted to normally retain the head 31 in one of the recesses 32 and thus lock the arm 27 in a set position. The arm 27 is provided on its outer side at a point spaced from its opposite end with a button or other fastening device 34 adapted to engage one vertical edge portion of the curtain 17. The portion of the curtain adjacent the arm 27 is provided with a horizontally disposed incision 35 thus forming a partly severed portion 36. The portion 36 of the curtain 17 is adapted to extend about the arm 27 and is secured thereto by a suitable fastening device 37.

As clearly shown in Fig. 4 the free end portion of the arm 27 is provided with a hooked end adapted to engage the bow 13 and thus provide a relatively rigid structure. A loop 37 is provided on the inner side of the arm 27 for facilitating the lowering and raising of this arm. In lowering the upper portion 19 of the curtain 17, the same is folded along the line 38 and is thus permitted to pass the side walls 12 of the top 11.

While I have shown and described the preferred embodiment of my invention, it is understood that I may make such minor changes in arrangement and construction of parts, as will remain within the spirit of the invention and the scope of the appended claims.

Having thus described my invention, what I claim is:—

1. The combination with a vehicle body having a top and a hinged door; of a socket secured to the inner side of the door; a curtain support having one end arranged in said socket; an arm horizontally hinged to the upper end of said support; curtain fastening devices carried by said arm, said curtain support, and said door; a curtain secured to the curtain support and to the said door and said arm, the upper portion of said curtain being adapted to be arranged inwardly of the side walls of the top, and extending to the transverse portions of the same, said hinged arm being adapted to be swung downwardly and inwardly to bring

the upper portion of the curtain below the top and thereby permit of the opening of the door; means to retain the hinged arm in a set position and an operating element carried by said hinged arm.

2. The combination with a vehicle body having a hinged door and a top, of a curtain support extending upwardly from said door and having its body portion flush with the outer surface of the door, curtain fastening devices carried by said curtain support and said door, an arm horizontally hinged to the upper end of said curtain support, curtain fastening devices carried by said arm, said arm having its upper end curved for engaging certain of the top bows, means to retain said arm in a set position, and a curtain secured to said curtain fastening devices, the upper portion of said curtain being arranged inwardly of the side walls of the top.

3. The combination with a vehicle body having a top and a hinged door, of a socket secured to the inner side of the door, a curtain supporting rod having its lower end portion arranged in said socket, a horizontally disposed arm carried by said curtain supporting rod, a fastening device carried by the outer end of said horizontally disposed arm, a hinged arm secured to the upper end of said curtain supporting rod, curtain fastening devices carried by said arm, said curtain supporting rod and said door, a curtain secured to said fastening devices, the upper portion of said curtain being arranged inwardly of the side walls of the top, said hinged arm being adapted to be lowered to bring the lower portion of the curtain below the top and thereby permit of the opening of the door, and means to lock said hinged arm in the desired position.

4. The combination with a vehicle body having a top and a hinged door, of a socket secured to the inner side of the door adjacent one vertical edge thereof, a curtain supporting rod having one end extending into said socket, an arm horizontally hinged to the upper end of said curtain supporting rod and adapted for engaging the bows of the top, means to retain said arm in a set position, a horizontally disposed supporting rod carried by said first named curtain supporting rod intermediate its ends, and a curtain detachably secured to said curtain supporting rod and said hinged arm, said hinged arm being adapted to be swung inwardly and downwardly for drawing the curtain below said top.

In testimony whereof I affix my signature in presence of two witnesses.

FRED J. ELERICK.
